UNITED STATES PATENT OFFICE.

CHARLES W. DAVISON, OF JEFFERSON CITY, MISSOURI.

DENTAL APPLIANCE.

1,001,362.

Specification of Letters Patent. Patented Aug. 22, 1911.

Application filed March 13, 1911. Serial No. 614,202.

To all whom it may concern:

Be it known that I, CHARLES W. DAVISON, a citizen of the United States, residing at Jefferson City, in the county of Cole and 5 State of Missouri, have invented certain new and useful Improvements in Dental Appliances; and I do hereby declare the following to be a full, clear, and exact description of the invention, such as will enable others 10 skilled in the art to which it appertains to make and use the same.

This invention relates to dental appliances and has for its object to produce an apparatus that may be attached to a dental chair 15 and connected to a source of air supply under pressure, for keeping a thin blast of air flowing between the face of an operator and that of his patient, for the purpose of preventing each from inhaling the other's 20 breath.

To these ends the invention consists in the novel details of construction and combinations of parts more fully hereinafter described, and particularly pointed out in 25 the claims.

Referring to the accompanying drawings forming a part of this specification in which like numerals designate like parts in all the views:—Figure 1 is a perspective view of 30 a portion of a dental chair, with a patient seated therein, and showing my invention applied to the head-rest and connected to a source of air supply; Fig. 2 is a plan view of my device, detached from the chair; Fig. 35 3 is an enlarged detail longitudinal sectional view taken on the line 3—3 of Fig. 2; Fig. 4 is an enlarged cross sectional view taken on the line 4—4 of Fig. 3; Fig. 5 is a view of a modified form of nozzle; Fig. 6 is a 40 view of another modified form of nozzle; and Fig. 7 is a view of a nozzle that is used for supplying air to the cavity of a patient's tooth to keep it dry while being filled.

1 indicates the back of a dental chair provided with the usual head-rest 2 to which is attached, to the arm 3, my improved dental apparatus 4. This apparatus consists of an arm 5 provided at one end with a collar 6 held in any adjusted position on the arm 3 45 by the set screw 7. The other end of this arm 5 is provided with a collar 8 which rigidly holds screwed therein a small cylinder 9, while 10 indicates a set screw for preventing the cylinder 9 from working loose. 50 A rod 11 carrying on one end a piston 12 is adapted to operate within the cylinder and

be held in an extended position by the spring 13 located between the end of said cylinder and said piston.

14 indicates a head piece provided with a 60 pad 15 and a collar 16 which collar is held by a set screw 17 on the other end of the rod 11. This rod is also provided with a stop 18 adapted to be adjusted along the screw threaded portion 19, to limit the movement 65 of the operating parts.

The cylinder 9 is reduced on its outer end to provide a bearing 20 for an arm 21, which arm is fulcrumed as at 22 and has attached thereto an air tube 23 which tube may be 70 made of a flexible metal, and may be provided with a valve 24. Said air tube is preferably of the shape shown; is adapted to extend, when in use, along the side of a patient's face, and is provided at its front 75 end with a nozzle 25. At its rear end it is further connected to a hose 26 which leads to a source of compressed air supply 27. Pivotally connected to the outer end of the arm 21 is a rod 28 which is pivotally connected to a stud 29 screwed into the piston 12, as clearly shown in Fig. 4. Said stud is adapted to travel in the slot 30 in the side of the cylinder 9 when the head piece 14 80 is operated.

The device when not in use is normally held by the spring 13 in the position shown by full lines in Fig. 2. When the patient's head comes into contact with the head piece 14 the air pipe 23 is caused to swing upward and inward to the position shown in Fig. 1. Its flexibility permits the tube now to be adjusted to the proper position so that a blast of air will not touch the patient's 90 face, but will at the same time prevent the 95 operator and patient from inhaling each other's breath.

On account of the flexibility of the air tube and the various adjustments, the device is capable of delivering a blast of air, from 100 any desired position, in front of a patient's face. Also, of course, any suitable form of automatic valve may be employed instead of the valve 24 and the device may be used for various other kinds of operations—for 105 instance, in shaving, massaging, etc.

The different nozzles as shown in Figs. 5 and 6 may be secured to the end of the air pipe to suit different requirements.

In the modification shown in Fig. 7, the 110 nozzle 31 is made relatively long and flexible so that when it is secured to the end of

the air tube it may be used for insertion into a patient's mouth for supplying air to the cavity of a tooth to keep it dry while filling.

From the foregoing, it may be seen that if 5 the above device is used, the offensive odor arising from a decayed tooth or a foul stomach of a person cannot reach the operator.

It is obvious that those skilled in the art 10 may vary the details of construction and arrangement of parts without departing from the spirit of my invention, and therefore, I do not wish to be limited to such features except as may be required by the claims.

What I claim is:—

- 15 1. In an apparatus of the character described the combination of a chair adapted to support a patient to be operated on; an adjustable spring actuated means connected to said chair comprising a tube and a piston in said tube adapted to deliver a flat blast of air between the face of said patient and the face of the operator, and thereby prevent each from inhaling the other's breath, substantially as described.
- 20 2. In an apparatus of the character described the combination of a chair adapted to support a patient to be operated on; an adjustable spring actuated means connected to said chair comprising a tube adapted to deliver a flat blast of air between the face of said patient and the face of the operator; and means connected to said tube adapted to be operated by said patient's head for throwing said tube into and out of operative position, substantially as described.
- 25 3. In an apparatus of the character described the combination of a chair adapted to support a patient to be operated on; adjustable means connected to said chair comprising a tube adapted to deliver a flat blast of air between the face of said patient and the face of the operator; and a spring actuated rod connected to said tube adapted to be operated by said patient for throwing said tube into and out of operative position, substantially as described.
- 30 4. In an apparatus of the character described the combination of a support adapted to hold a patient to be operated on; an adjustable spring actuated means connected to said support comprising a bent flexible tube; a flexible nozzle mounted on one end of said tube; a means adapted to be operated by the patient's head for throwing said tube into and out of operative position; and a means connected to said tube for delivering a blast of air thereto, substantially as described.
- 35 5. In an apparatus of the character described the combination of a support adapted to hold a patient to be operated on; an adjustable spring actuated means connected to said support comprising a bent flexible tube; a flexible nozzle mounted on one end of said tube; a means adapted to be operated by the patient's head for throwing said tube into and out of operative position; and a means connected to said tube for delivering a blast of air thereto, substantially as described.
- 40 6. In an apparatus of the character described the combination of a support adapted to hold a patient to be operated on; an adjustable spring actuated means connected to said support comprising a bent flexible tube; a flexible nozzle mounted on one end of said tube; a means adapted to be operated by the patient's head for throwing said tube into and out of operative position; and a means connected to said tube for delivering a blast of air thereto, substantially as described.
- 45 7. In an apparatus of the character described the combination of a support adapted to hold a patient to be operated on; an adjustable spring actuated means connected to said support comprising a bent flexible tube; a flexible nozzle mounted on one end of said tube; a means adapted to be operated by the patient's head for throwing said tube into and out of operative position; and a means connected to said tube for delivering a blast of air thereto, substantially as described.

4. In an apparatus of the character described the combination of a chair, provided with a head-rest, and adapted to support a patient to be operated on; means connected to said head-rest comprising an arm; a cylinder mounted on said arm; a tube connected to said cylinder adapted to deliver a blast of air between the face of said patient and the face of the operator; and a spring actuated rod mounted within said cylinder adapted to be operated by said patient for throwing said tube into and out of operative position, substantially as described.

5. In an apparatus of the character described the combination of a chair, provided with a head-rest and adapted to support a patient to be operated on; adjustable means connected to said head-rest comprising an arm; a cylinder mounted on said arm; a lever pivotally connected to said cylinder; a tube mounted on said lever; a spring actuated piston mounted within said cylinder; a rod connecting said lever and said piston; and a means connected to said tube adapted to deliver a blast of air between the face of the patient and the face of the operator, substantially as described.

6. In an apparatus of the character described the combination of a support adapted to hold a patient to be operated on; an adjustable spring actuated means connected to said support comprising a bent flexible tube; a flexible nozzle mounted on one end of said tube; a means adapted to be operated by the patient's head for throwing said tube into and out of operative position; and a means connected to said tube for delivering a blast of air thereto, substantially as described.

In testimony whereof, I affix my signature, in presence of two witnesses.

CHARLES W. DAVISON.
